UNITED STATES PATENT OFFICE

2,412,789

UNIT LOCK

Henry G. Voight, Hamden, Conn., assignor to Sargent & Company, New Haven, Conn., a corporation of Connecticut

Application October 4, 1943, Serial No. 504,818

2 Claims. (CL. 292—359)

1

This invention relates to door locks, and more particularly to a so-called unit door lock similar, for example, to that shown in my prior Patent No. 2,304,612, granted December 8, 1942. In that patent there is disclosed a lock system wherein is provided a case adapted to be used for a number of locks of different types, and various lock parts or elements designed to be interchangeably mounted in the case so that by the use of the proper elements or mechanism the desired type of lock could be constructed.

Unit locks of this character usually employ a mounting plate or supporting plate constituting a part of the case, and a face plate forming the front of the lock case through which the bolt projects, which face plate is formed integrally with the supporting plate carrying the mechanism. This supporting plate forms one wall of the lock case, and a cover plate is secured thereto in spaced relation to form the opposite wall, which walls, with the face plate, form the case. In my patent, above referred to, it was necessary when different types of locks were to be made to form the proper openings in the face plate of the lock for the bolts or other projecting parts depending upon the type of lock which was to be made. This, of course, required some work to be done upon the case after its original manufacture, so that the case as originally made was not complete. In the present instance the lock case as originally made is equipped with all of the openings which may be required for the various bolts. In other words, there will be formed in the face plate an opening for a latch bolt, and upper and lower openings for dead bolts or stop bolts or dog-actuating members, or other elements which may be employed and which project through the face of the lock. As not all of these elements are used in every lock, and as it would be unsightly to have openings in the face plate of the lock which are not employed, I secure a mask or scalp plate over the face plate of the lock, this mask or scalp plate containing the openings which are necessary for the particular type of lock which is to be manufactured. In this manner the case of the lock is exactly the same for any one of a number of different types of locks. The mask or scalp plate, however, will be individual to the particular lock, and while it will contain openings which will register with those which are desired to be used, it will conceal those openings which are not to be used.

Also I have provided a lock of this type with a knob-dogging mechanism mounted upon one of the side walls of the lock case instead of being

2

mounted in the face plate of the lock, as is usually the case with unit-type locks.

One object of the invention is to provide a lock case which may be employed with any one of a number of different locks.

10 A further object of the invention is to provide a lock case which is universal in character in that it may be employed with a number of locks of different types, such case being provided with a mask or scalp plate of substantially the same size and shape as the face plate of the lock, which scalp plate will contain only the face openings necessary for the particular lock which is to be made, and which will conceal the remaining 15 openings in the face plate of the case itself.

20 A still further object of the invention is the simplification and the cheapening of the manufacture of locks by providing a universally usable lock case which may be kept in stock in quantity and used in the manufacture of a number of different locks.

25 A still further object of the invention is to provide a new and improved stop or knob-dogging mechanism mounted upon the side wall of the lock case between this wall and the escutcheon plate whereby the actuating elements of the dogging mechanism will project through the face of the door at the side of the knob.

30 To these and other ends the invention consists in the novel features and combinations of parts to be hereinafter described and claimed.

In the accompanying drawings:

Fig. 1 is a vertical sectional view of a lock embodying my improvements;

35 Fig. 2 is a sectional view on line 2—2 of Fig. 1;

Fig. 3 is a sectional view on line 3—3 of Fig. 1;

Fig. 4 is an elevational view of the stop or dogging mechanism mounted on a wall of the case;

40 Fig. 5 is a view partly in section on line 5—5 of Fig. 4;

Fig. 6 is a front or edge view of the lock case shown in Fig. 1;

Fig. 7 is a sectional view on line 7—7 of Fig. 2. 45 showing the face plate of the lock case;

Figs. 8, 9, 10 and 11 are front elevational views of masks or scalp plates of various types; and

Fig. 12 is a top plan view of the scalp plate shown in Fig. 8.

50 To illustrate a preferred embodiment of my invention I have shown a lock case mounted in position upon the door 10. The lock case comprises a mounting or supporting plate 11 having a front face 12 formed integrally therewith and 55 forming the front of the case. The plate 11

forms one side wall of the case, the opposite wall being formed by the plate 13 which is secured by screws or the like to posts 13^a formed upon the plate 11. As is usual in locks of this type, the front plate projects beyond the cover plate 13 (Fig. 2), so that its inner edge is substantially flush with the face of an escutcheon plate 14, which escutcheon plate is secured by screws 15 to the outer escutcheon plate 16, the latter being in turn secured to the supporting plate 11 by screws 17 passing through the latter plate and entering posts 18 formed on the escutcheon plate 16. The escutcheon plates may also be secured to the door after the lock has been set into place by screws 19.

The lock mechanism is mounted between the plates or front and rear walls 11 and 13, and the mechanism employed will, of course, vary depending upon the type of lock which is to be made. As shown for purposes of illustration, the lock mechanism consists of a latch bolt 20 to which is connected a retracting yoke 21 having laterally turned ends 22 designed to be engaged by the rollbacks 23, 24 and 25. As shown in Fig. 3, the rollback 24 is formed integrally with a central hub 26, while the rollbacks 23 and 25 are rotatably mounted on reduced end portions of this hub.

Knob sleeves 28 and 29 are secured to the case, and the shank 30 of the inside knob is rotatably mounted in the sleeve 29. Secured to the knob is a stem 31 of non-circular cross section, which stem enters a non-circular opening in a hub 32, also rotatably mounted in the sleeve 29, which hub engages the rollback 25 to actuate the latter, as shown in Fig. 2, and as is well understood in the art.

The outside knob is shown at 33 and is provided with a shank 34 rotatably mounted in the sleeve 28, the inner end of which shank engages the rollback 23 so that this rollback is actuated by the outside knob, it being understood that each of the rollbacks may be actuated independently of the others, as the rollbacks 23 and 25 are rotatably mounted on the hub 26.

Mounted in the outside knob is a cylinder lock 35 to the key barrel of which is secured a stem 36 of non-circular cross section, which stem is received in a similarly shaped opening in the hub 26, so that this hub and rollback 24 thereon are actuated by the lock at the outside of the door.

The latch bolt 20 is provided with a head 40 projecting through an opening 41 in the face plate 12. It will be seen by reference to Fig. 7 that this face plate is not only provided with the opening 41 for the latch bolt, but is provided with an additional opening 42 of rectangular shape, and also an opening 43 which is generally of rectangular shape but which may be enlarged adjacent its ends, as shown at 44, so that the lock case consisting generally of the members 11, 12 and 13 may be used with other types of locks.

In order, however, to conceal the openings of the face plate which may not be used in any particular lock, I provide a scalp plate 45 in which are formed only the openings which are to be used with the bolts or other elements with which the lock is provided. For example, the face plate 45 to be used with the lock shown in Figs. 1 to 3 is provided only with an opening 46 registering with the opening 41, and, as shown in Fig. 6, conceals the openings 42 and 43. The face plate is substantially of the same length and width as the front plate 12 of the lock case, and as shown

in Figs. 2 and 12, is provided with a laterally extending end flange 47 designed to lie against the mounting plate or wall 11 and to extend snugly into a space between this plate and the escutcheon 16 at the outside of the door. The plate 45 may be secured to the plate 12 in any suitable manner such as by rivets 48.

If it is desired to construct a lock suitable, for example, for a bathroom door, a plate such as that shown in Fig. 8 at 45^a is employed instead of the plate 45. This plate contains the opening 46 for the latch bolt and an additional opening 49 through which a dead bolt may project, and it will, of course, be understood that in this event a dead bolt would be included in the lock case in addition to the latch bolt.

In Fig. 9 of the drawings there is illustrated a further type of mask or scalp plate 45^b to be used with a lock for a communicating door, which plate will be provided with the opening 46 for the latch bolt and upper and lower openings 49 and 49^a for a pair of dead bolts, as is usual in locks for communicating doors. The openings 49 and 49^a are adapted to register with the openings 42 and 43 in the plate 12, respectively.

In Fig. 10 of the drawings I have shown a scalp plate 45^c adapted for use with a front door lock. This plate is provided with the openings 46 and 49 which will register with the openings 41 and 42 of the plate 12, and is also provided with circular openings 50 and 51 to accommodate push buttons which will be used with an interior latch or knob-dogging mechanism. These openings will register with the enlargements 44 of the opening 43 in the front plate 12.

In Fig. 11 I have shown a scalp plate 45^d for use with a vestibule door lock, which plate will be provided with openings 46, 50 and 51.

I have also provided a dogging mechanism for the latch bolt which may be mounted upon one of the walls of the lock case, and may be employed in place of the dogging mechanism operated by the push buttons adapted to extend through the openings 50 and 51 in the plates 45^c and 45^d. If this novel dogging mechanism is employed, the openings 50 and 51 may be omitted. As shown more particularly in Figs. 2, 4 and 5, this dogging mechanism is mounted upon the plate 13 forming the inner wall of the lock, and is housed between this plate and the escutcheon 14. A plate 55 is secured to the plate 13 and disposed in spaced relation thereto, the plate 55 lying between the plate 13 and the escutcheon 14. Between the plates 13 and 55 is pivotally mounted a walking beam 56, this member being provided with an opening 56^a receiving the knob shank and with a pair of circular bearing members 57 rockably mounted in openings 58 and 59 in the plates 13 and 55, respectively. Mounted upon the ends of the walking beam are push buttons 60 and 61 which extend through the escutcheon 14 at the inner face of the door for manual operation.

To the inner end of the push button 61 is secured a slide 62 which carries a dogging member 63 adapted when projected outwardly or toward the outer knob to project into a recess 64 in the shank 34 of the outside knob to dog the knob against movement. The portion of the slide 62 adjacent the push button 61 is provided with recesses 65 adapted to be engaged by a spring-pressed ball detent 66 mounted on the plate 13 to releasably hold the dogging mechanism in either inoperative or operative position against accidental displacement. A body portion 67 of the slide 62 extends through an opening in the

wall 11 of the lock case so as to be guided thereby in its sliding movements.

It will be understood that the push buttons 60 and 61 extend through the escutcheon plate 14 at the inside of the door adjacent the inner knob (not shown), where they may be readily accessible for manual operation. It is believed that the operation of the lock will be readily understood from the foregoing description. With the push buttons 60 and 61 in the position shown in Fig. 2, the latch bolt is free to be retracted by either the inner or outer knobs, and the dogging mechanism is held against accidental displacement from this position by the engagement of the detent 66 in one of the recesses 65. If, however, the push button 61 is pushed inwardly, the slide 62 will be moved toward the outer knob, and the dogging element 63 will enter the recess 64 in the knob shank and dog the outer knob against rotation. In this position of the parts the latch bolt may not be retracted by the outer knob, but may be retracted by the inner knob, or by means of the key-operated lock 35 at the outside of the door, which rotates the stem 36 and therefore the hub 26 carrying the rollback 24.

While I have shown and described some preferred embodiments of my invention, it will be understood that it is not to be limited to all of the details shown, but is capable of modification and variation within the spirit of the invention and within the scope of the claims.

What is claimed is:

1. A door lock comprising a case adapted to

be secured to a door and having opposed inner and outer side walls, a bolt reciprocably mounted in the case, inner and outer knobs for retracting said bolt, inner and outer knob sleeves secured to said inner and outer side walls respectively within which said knobs are rotatably mounted, a dogging member movably mounted in the case for dogging said outer knob, a walking beam pivotally carried by said inner wall and connected to said dogging member, actuating means for said walking beam accessible for operation at the inside of the door, and said walking beam comprising a plate-like member having an opening receiving said knob sleeve and being pivoted on an axis intersecting the axis of said sleeve.

2. A door lock comprising a case adapted to be secured to a door and having opposed inner and outer side walls, a bolt reciprocably mounted in the case, inner and outer knobs for retracting said bolt, inner and outer knob sleeves secured to said inner and outer side walls respectively within which said knobs are rotatably mounted, a dogging member movably mounted in the case for dogging said outer knob, a walking beam pivotally carried by said inner wall and connected to said dogging member, actuating means for said walking beam accessible for operation at the inside of the door, and said walking beam comprising a plate-like member having an opening receiving said knob sleeve whereby the opposite ends of said member lie on opposite sides of the sleeve.

HENRY G. VOIGHT.
